LEO LORENZ, OF MUSKEGON, MICHIGAN, ASSIGNOR TO ANACONDA WIRE AND CABLE COMPANY, OF NEW YORK, N. Y., A CORPORATION OF DELAWARE

ROLL FOR WIRE DRAWING MACHINES

Application filed January 27, 1931. Serial No. 511,467.

This invention relates to improvements in wire drawing machines and aims particularly to provide a drawing roll made of light parts including removable wear-resisting rings which can be readily detached and replaced as they become worn from service.

Heretofore wire drawing rolls have been formed in a single piece having a plurality of steps of different diameters. In the drawing of wire, it is essential that the outside diameter of the successive steps be maintained uniform. The relationship between the diameters of the successive steps is commensurate with the reduction of diameter and elongation of the wire drawn. Heretofore when the steps of the roll became slightly grooved or worn, it has been found necessary to turn down or grind each of the several steps. Such turning down or altering of the diameters of the steps of the drawing rolls naturally changes the draft of the entire wire drawing machine. This results in the necessity of making many alterations and changes and also causes considerable confusion.

My improved wire drawing roll includes a plurality of rings whose diameters vary by predetermined increments and these rings are removably mounted on suitable supporting members which are adapted to be rotated by any suitable means. The rings are preferably though not necessarily made of hardened or tempered spring steel which has a greater resistance to wear than ordinary turned cast iron or steel drawing rolls heretofore made. However, when any one ring of a plurality of rings becomes grooved or worn the individual ring can be removed and discarded and a new one substituted without changing the draft of the machine as a whole.

The above and other features of improvement will be fully apparent from the following specification when read in connection with the accompanying drawings and will be pointed out with particularity in the appended claims.

In the drawings:—

Fig. 1 is a skeleton view illustrating sufficient elements of a wire drawing machine

necessary for an understanding of the invention;

Fig. 2 is an enlarged longitudinal sectional view through a wire drawing roll embodying the invention;

Fig. 3 is an enlarged detail illustrating features of construction;

Fig. 4 is a fragmentary section on line 4—4 of Fig. 2.

Referring in detail to the drawings, the wire drawing machine includes a plurality of drawing rolls, indicated at A, B, C, D, E and F. A supply reel S carries the wire which is to be reduced in diameter. This wire is drawn by the rolls A, B, C, etc., through dies R, R', R², R³, etc., in a manner to be herein-after described and the final product is a wire of greatly reduced diameter which is reeled up on a take-up roll T.

The rolls A, B, C, etc., are of similar construction and a detailed description of one will suffice for all. As illustrated particularly in Fig. 2, the drawing roll comprises a plurality of rings numbered 1 to 6 inclusive. These are of different diameters, ring 1 being the smallest and ring 6 being the largest. These diameters increase by varying non-uniform increments, the increment between any two rings depending upon the cross sectional reduction of the wire and the elongation thereof. While not wishing to be limited thereto, I prefer to form the rings of spring steel which may be suitably tempered or hardened in order to resist wear. The rings are detachably mounted preferably being seated in grooves of special form. For example, the ring 1 is seated between a collar 7 and a disc 8, the collar having a groove 7^a therein and the disc 8 having a similar groove 8^a therein.

On its opposite face, the disc 8 is provided with a groove 8^b. The ring 2 is held between the disc 8 and another disc 9 which is similarly grooved. In like manner, the discs 3, 4, 5 and 6 are held in assembled relationship with the discs 9, 10, 11, 12 and 13. All of the discs are provided with a central aperture or bore 14 which engages a supporting shaft 15 which may be driven by any suitable power mechanism. Extending longitudinally or in a direction parallel to the axis of the rings there

are a plurality of through bolts 16 which pass through suitable holes formed in the discs 8 to 13 inclusive. The ends of the bolts 16 are threaded as at 16^a for engagement in 5 a suitably threaded opening in the collar 7. A head 17 on the extremity of each bolt 16 engages the surface of the largest disc 13 as clearly indicated in Fig. 13. As thus arranged, it is clear that the several bolts 16 10 detachably hold the rings 1 to 6 inclusive in proper engagement with the grooved seats formed in the supporting collar 7 and discs 8 to 13. In the event that any given ring becomes worn or grooved in use. The particu- 15 lar worn ring can be readily removed merely by disconnecting the bolts 16 and a new ring can be substituted. It will be understood that such a replacement of a new ring will not necessitate disturbing the diameter of the re- 20 maining rings as has heretofore been necessary when the drawing rolls were made of a single piece in which case all of the steps would have to be turned or ground down in order to maintain the proper increment be- 25 tween the diameters of the various steps of the roll.

The centering seats for the rings are preferably of slightly undercut form, as illustrated in Fig. 3 so as to ensure a close tight 30 fit between the ring and the adjacent supporting disc. The slot 8^a illustrated in Fig. 3 is of annular, triangular form. The angle of undercut is slightly exaggerated as indicated at α in Fig. 3. This angle in practice 35 will usually be about 3° . As thus undercut, the innermost portion 18 will be of slightly greater diameter than the outside diameter of the ring. In this way, a clearance will be provided so that the corner 19 can make an 40 extremely snug fit against the outer periphery of the ring. The face 20 of the triangular groove 8 is disposed at an angle γ of about 60° . This angular form of slot serves as a guide for assembling or forcing the parts into 45 position and provides a construction whereby the tightening up of bolts 16 wedgingly presses the outer periphery of the ring against the corner 19. This wedging action being possible due to the inclination of the surface 50 20 and the relieved or undercut angle α . In wire drawing machinery, it is important that such a tight joint between the ring and the disc are secured so that there will be no opportunity for the drawn wire to catch at the 55 point of junction between the ring and the disc.

In operation, the wire to be drawn from the supply reel S first passes through the die R. It is then wrapped several times 60 around the ring 1 of the roll A. It then passes through a suitable die opening in the die R' and around the ring 1 of the roll B. It is wrapped several times around the ring 1 and then passes through another die opening in the die R', thence around the ring 2

of the roll A. Then again through another opening in the die R' and around ring 2 of the roll B. And so on for the various rings of the rolls A and B. From the largest ring of the roll B, the wire then passes through the die R² to the smallest ring of the roll C. It is wrapped several times around this ring and then passes through die R³ to the No. 1 ring of roll D and so on finally from the largest ring of roll D through die R⁴ and in 7 a manner similar to that above described around the rings of the rolls E and F through the die R⁵. At each pass through the die, it will be understood that the wire is reduced in diameter and at the same time 8 elongated. It will also be understood that the increment of increase in diameter between the various rings is commensurate with the reduction in cross section of the wire. The final product is reeled up by any suitable means on a take-up reel T. From the foregoing, it will be understood that when any given ring becomes grooved or worn in use it can be replaced without the necessity of replacing any other rings. It will also be understood that because of the peculiar undercut seats formed in the discs, the rings can be closely seated in contact with the discs in such a way as to prevent any likelihood of the wire catching therein. 9 The skeleton construction described is also of extremely light weight which is advantageous in machines for drawing very fine wire as it permits rotation of the parts at a high rate of speed without material loss of power and with a minimum vibration.

While I have described with great particularity the specific details of the various embodiments of the invention herein illustrated it is not to be construed that I am limited thereto since various changes and substitution of equivalents may be made without departing from the invention as defined in the appended claims.

What I claim is:—

1. A wire drawing machine roll adapted to draw a wire through a die to reduce the diameter of said wire, comprising a ring about which the wire is adapted to be wrapped, a disc having a triangular undercut annular groove adjacent its periphery forming a seat for engagement with an edge of the ring and means for forcing the ring tightly in engagement with said seat to cause the outer periphery of the ring to abut tightly against the outer edge of said groove.

2. A roll of the character described comprising a plurality of discs having respective annular grooves adjacent their peripheries 1 undercut in cross section and forming seats, rings engaging said seats and means for clamping the rings and discs in assembled relationship, whereby the outer edge of each undercut groove is held firmly in abutment

with the outer periphery or operative surface of each ring.

3. A roll of the character described comprising a pair of discs, each having a groove adjacent its periphery undercut in cross section, a thin spring steel ring whose opposite edges enter the grooves in said discs and bolts passing through said discs and detachably securing the parts in assembled relationship, said bolts holding said discs firmly against the edges of said rings with the outer edges of said grooves engaging the outer periphery of said rings.

In witness whereof, I have hereunto signed
15 my name.

LEO LORENZ.
